UNITED STATES PATENT OFFICE

105,456

DESIGN FOR A DRESS ENSEMBLE

Louis Katz, New York, N. Y.

Application June 23, 1937, Serial No. 70,015

Term of patent 3½ years

To all whom it may concern:

Be it known that I, Louis Katz, a citizen of the United States of America, residing in Manhattan, county of New York and State of New York, have invented a new, original, and ornamental Design for a Dress Ensemble, of which the following is a specification, reference being had to the accompanying drawing, forming part thereof, wherein,

The rear portion of the jacket unit is conventional.

I claim:

The ornamental design for a dress ensemble, substantially as shown and described.

LOUIS KATZ.
